SWIMMING TRUNKS

Harry Spack, Washington, D. C.

Application March 8, 1946, Serial No. 652,968

1 Claim. (Cl. 9—20)

1

My invention relates to new and useful improvements in swimming trunks, and more particularly to swimming trunks that are capable of inflation to produce buoyancy, the primary object being to provide a garment of this character which in general appearance is the same as an ordinary pair of swimming trunks and for general use may be utilized the same as an ordinary pair of swimming trunks, but in which provision is made for the introduction of air to certain parts thereof, so that the wearer may use the same for swimming or floating without danger of sinking or drowning.

A further object of the invention resides in the provision of a pair of swimming trunks designed with pockets located at strategic points therein for the introduction of air thereto.

A further object of the invention resides in the provision of swimming trunks having pockets for the reception of air, portions of which pockets are capable of extension to form wing-like portions and adapted when in dis-use to be inverted and concealed.

Still another object of the invention resides in the provision of an inflating tube with means formed in the garment for the concealment thereof when said tube is in dis-use.

A still further object resides in the provision of a pair of swimming trunks which are simple and inexpensive to manufacture and one which will prove effective in use.

With these and numerous other objects in view, my invention consists in the novel features of construction, combination and arrangement of parts as will be hereinafter referred to and more particularly pointed out in the specification and claim.

In the accompanying drawings, forming a part of this application:

Fig. 1 is a perspective view showing my improved swimming trunks applied to use on a wearer under normal conditions.

Fig. 2 is an enlarged fragmentary front elevation, with parts broken away and parts in section, showing the pocket at the waist band in open position with the inflating tube removed and adapted to be used for introduction of air to parts of the garment.

Fig. 3 is an enlarged fragmentary sectional view taken vertically through the garment before it is finished and showing particularly the inside of the waist band with the belt therein.

Fig. 4 is a rear elevation of the garment, with parts broken away and parts in section, showing the wing-like pocket sections in extended positions and inflated.

2

Fig. 5 is a front elevation of the garment with the pockets inflated, and

Fig. 6 is a horizontal section, enlarged, taken along the line 6—6 of Figure 3 through the portion of the garment having the pocket therein, with the wing-like pocket portion inverted and concealed.

I have discovered that a large number of persons are unable to swim and for such reasons do not visit swimming pools and the like and do not obtain the enjoyment of and the exercise obtained from swimming. I have also discovered that many persons would indulge in swimming if some convenient means were provided to assist non-swimmers in their efforts, and to make the possibility of drowning nil. I have also discovered that disabled veterans who have lost limbs and arms are finding it difficult to enjoy swimming, due to the lack of a facility to aid them while in the water. It is for these reasons that I have invented my new swimming trunks which, under normal conditions, may be worn and used as any ordinary pair of swimming trunks but which, when inflated, may be utilized to assist in swimming or floating without danger of drowning.

In describing my invention I shall refer to the drawings, in which similar reference characters designate corresponding parts throughout the several views, and in which the numeral 1 represents the front of a pair of swimming trunks, which front is composed of the two sections 2 and 3 stitched together in the front, as shown at 4, and also stitched together at the crotch section, as shown at 5. The rear portion of the garment comprises the two sections 6 and 7 secured together centrally and vertically as at 8, the crotch section being stitched, as at 5, to the front section 1. A waist band portion 9 formed on the front and rear portions of the garment has an inside strip 10 secured therein, forming a circular pocket through which is extended the belt 11, which is adjustable in the front as shown at 12. Openings are provided in the strip 10 at certain points throughout the length thereof, as shown by the numeral 13, whereby the belt 11 may be observed and adjusted or removed when desired. The side edges of the front and rear portions of the garment are stitched together at their upper and lower ends, as shown at 14 and 15.

On the inner face of the front 1 of the garment, there is stitched a strip of material 16, which is substantially of inverted U-shape, the stitching to the front portion being designated by the numeral 17. This provides a substantially inverted U-shaped pocket within the garment, the side portions of which are of greater width than the

horizontal portion thereof, which horizontal portion extends just below the waist band of the garment. Connected to the pocket so formed, through the waist band portion of the garment, with an airproof connection, is an inflating tube 18, in the free end of which is provided a valve, not shown. This inflating tube is adapted to be ordinarily concealed from view in a pocket formed in the waist band portion by the stitching of a covering strip 19 to the front of the waist band. This covering strip is slotted horizontally for a portion of the length thereof and the edges thereof provided with portions of a separable fastener of the zipper type, as shown at 20. Thus the tube when not in use may be concealed from view but made available quite readily when it is desired to inflate the garment.

Probably the inverted U-shaped pocket for the reception of air would be sufficient to serve all desirable purposes, but I have designed a further means of aiding in the utilization of this garment for floating and swimming which will add to the buoyancy of the wearer and act as a safeguard to sinking. To this end I provide the wing-like extensions 21 and 22, which form extensions of the pocket portion of the garment. In fact, these extensions are extensions of the front sections 2 and 3 and the depending side portions of the air pockets and have their rear walls united with the material forming the air pocket and their front walls connected with edges of the front sections 2 and 3 of the garment. When extended as shown in Figures 4 and 5, they form pontoon sections having communication with the inverted U-shaped pocket. These extensions 21 and 22, however, may be disposed to an inverted position, as shown in Figure 6, so as to be concealed within the substantially vertical portions of the air pocket, and separable fasteners 23 are provided on portions of these extensions 21 and 22 to secure the latter in the inverted position. When these extensions 21 and 22 are in their retracted positions, they form pockets for the reception of the hands or other articles and by pressing the snap fasteners together, the pockets may be held closed and loss of articles placed therein will be prevented.

In operation, these swimming trunks have the extensions 21 and 22 thrust inwardly to the inverted or retracted position under normal conditions and secured by the fasteners 23, so that the garment may be used as any other pair of swimming trunks. In Figure 1 I have shown the application of the garment to use on the body of a wearer under normal conditions. When it is desired to inflate the garment, the wearer enters the water up to his waist line or otherwise wets the garment thoroughly. The garment is made of a closely woven material and it is a known fact that such material when wet will retain the air within a thoroughly covered area for an appreciable length of time. Having thoroughly saturated the garment with water, the portions 21 and 22 are extended; the inflating tube 18 is removed from the waist line pocket its outer end thrust into the mouth of the person wearing the garment, and air is blown into

the garment through said tube. The air will circulate through the inverted U-shaped pocket aforesaid, and into the wing-like portions 21 and 22, whereupon the tube is returned to the waist line pocket and concealed from view. When so inflated the garment will take the appearance of that shown in Fig. 5 of the drawing. Such a garment when worn will keep the body afloat for an appreciable length of time and assisting the wearer learning to swim or float on the surface of the water, without danger of drowning. When the wearer notices any leakage of air, he may apply more air to the pocket in the manner aforesaid.

From the foregoing description of the construction of my improved garment, the method of constructing and applying same to use will be readily understood, and it will be seen that I have provided a comparatively simple, inexpensive and efficient means for carrying out the various objects of the invention.

While I have described the elements best adapted to perform the functions set forth, it is apparent that various changes in form, proportion and in the minor details of construction may be resorted to, without departing from or sacrificing any of the principles of the invention.

Having thus described my invention, what I claim is:

30 A pair of swimming trunks having front and rear sections and having vertically extending side openings, a sheet of material applied to the inner face of the front section to provide an air pocket extending across the garment and downwardly along sides of the front thereof with its side edges following front edges of the side openings, bag-like extensions for said air pocket closed at outer ends and having front and rear walls, the rear walls of said bags being united with side edges of said sheet and their front walls being secured to edges of the front section along front edges of the side openings, said extensions being foldable inwardly and insertable through the downwardly extending side portions of the side 40 openings into the air pocket for forming article receiving pockets having openings between the front and rear sections of the trunks, fasteners for releasably holding the side openings of the article receiving pockets closed and thereby forming 45 closures for outer ends of the inserted article-receiving pockets, and means for inflating said air pocket and forcing the bag-like extensions to an extended and inflated position.
